RE-ENTRY BODY SUPPORT

Tsoy K. Moy, Santa Clara, Calif., assignor, by mesne assignments, to the United States of America as represented by the Secretary of the Navy

Filed Nov. 13, 1962, Ser. No. 237,411

1 Claim. (Cl. 89—1.7)

This invention pertains generally to shock absorbing and supporting structure for an irregularly shaped mass which is to be constrained against movement with respect to a containing housing therefore. More particularly it relates to instrumentalities for providing support for a missile contained in a missile launching tube.

Guided missiles of the variety which are adapted for launching from a tube are commonly loaded into a launching tube a substantial period of time prior to launching and are maintained therein until fired. During the time in which a missile is maintained or stored in the launching tube, it often becomes desirable to move the assemblage. This is particularly true when the launching tube is located on board a transportable launcher, such as a seagoing vessel, and more particularly a submarine. In such an environment the launching tube structure may be fixed with respect to the structure of the submarine or vessel. During such transportation of a launcher with a missile therein, the missile is often subjected to shocks and vibrations within the tube, and it is therefore desirable to provide means to support and shield the missile, especially the re-entry portion thereof. In the past, various mechanically retractable devices have been proposed, such as tensioned cables that support the missile and retain it in desired position in the tube. However, these mechanically retractable devices present certain disadvantages and shortcomings and are possessed of undesirable features which result from the fact that they must be quickly and reliably released and completely withdrawn. Failure to do so will result in damage to the missile and possible invalidation of the launch.

Additionally, excessive shock on the re-entry body, which is generally positioned on the nose or forward end of the missile, has been encountered due to the impact of water upon the missile and the high pressure gas trapped between the inflowing water and the outwardly expelled missile during underwater launches.

It is, therefore, an object of the present invention to provide new and improved instrumentalities for isolating a missile against externally induced vibration and forces to which it would otherwise be subjected and supporting it in a manner whereby it will be immune to externally applied shock effects and which instrumentalities do not require the incorporation of facilities for release and withdrawal with respect thereto prior to launching of the missile.

It is a further object of the present invention to provide a support for a missile which will not foul the launching tube during launching as well as after the missile has been ejected.

A further object is the provision of an improved vibration isolating and mass supporting system which is possessed of substantially all of the desired essential operational features of devices for similar purposes heretofore or now in general use and which obviates substantially all of the undesirable features or shortcomings thereof and which possesses all of the qualities of compactness, ruggedness, adaptability and durability.

It is a further object of the present invention to provide a lateral supporting and positioning structure for

2

the missile which will effect a reduction in the peak pressure exerted on the cone section of a missile during the initial portion of a launch, especially when such launch is made underwater.

5 A further object of this invention resides in the provision of a vibration isolation system in which the elements to be protected from ambient induced vibrations are so supported within a containing structure having a common or intimately disposed base with respect to the device to be protected whereby undesirable vibrations are not transmitted to the device but are effectively damped or absorbed by the novel lateral supporting structure in which only relatively light weight supporting instrumentalities are required to provide the desired results, thereby providing a structure which does not add undue dead weight to the automotive vehicle or vessel carrying the system.

Other objects and many of the attendant advantages of this invention will be readily appreciated as the same becomes better understood by reference to the following detailed description when considered in connection with the accompanying drawings in which like reference numerals designate like parts throughout the figures thereof and wherein:

20 FIG. 1 is a perspective view of a portion of a missile launching tube assembly with portions broken away showing a missile and one modification of the supporting structure of the instant invention;

25 FIG. 2 is a transverse sectional view of a portion of the missile launching tube assembly taken substantially along the line 2—2 of FIG. 1 showing the missile nose and the supporting structure of the instant invention;

30 FIG. 3 is an enlarged exploded perspective view of the components of a portion of the missile supporting structure of the instant invention;

35 FIG. 4 is a transverse sectional view of a portion of the launching tube assembly missile and supporting structure showing a missile access opening taken substantially along the line 4—4 of FIG. 1, and

40 FIG. 5 is a transverse sectional view of a portion of the launching tube assembly, missile and supporting structure showing other missile access openings taken substantially along the line 5—5.

45 Referring now to the drawings, a launching tube assembly 10 embodying the invention, as shown in FIG. 1, comprises an outer tube 12 secured partially or wholly within a transporting vehicle (not shown). This vehicle generally a seagoing vessel such as a submarine, may house a plurality of launching tube assemblies and provision is made to retain the outer tube within the submarine with appropriate sealing provisions disposed between the vehicle and tube. For this purpose the outer tube terminates at its upper end in an outwardly extending flange 14 for engagement with a corresponding annular shoulder located on or near the upper surface of the submarine.

50 An inner or launching tube 16 is suspended within the outer tube by means of flex rods or the like as disclosed in application Serial No. 138,534 "Vibration and Noise Control in Liquid Springs," filed September 13, 1961, by Wilson T. Price et al. The space between the outer and launching tubes is sealed to prevent the entry of water therein. This seal is accomplished by means of an annular sealing member 18 disposed between the tubes at their upper ends.

55 A diaphragm 20 is releasably secured at the upper end of the launching tube to form an enclosure for preventing the entry of water into the launching tube. The dia-

phragm is secured to the tube by means of an annular flange 22 containing a suitable explosive charge, e.g. "Pramacord," which, upon detonation effects the release of the diaphragm.

A missile 24 is carried within the launching tube and is releasably secured within the tube by suitable clamping means normally associated with the missile skirt (not shown). The clamping structure is suspended near the lower end of the launching tube by structural arrangement which provide a limited degree of freedom of movement of the missile in order that bending stresses, vibration and shock imposed on the missile may be minimized. Additionally, resilient launch/stowage adapters (not shown) are located between the missile and launching tube at intervals along the missile body to absorb vibration and shock resulting from handling of the assembly and ship movements.

A nose cone or re-entry body 26, 28 is located on the forward end of the missile. Due to the particular components contained therein, the re-entry body is especially susceptible to damaging pressures and shocks. As pointed out hereinabove, these induced shocks on the missile may originate during handling and stowage of the missile and associated launching tube container 16, or may be caused by various maneuvers of the submarine within which the launching tube assemblies reside. A further pressure shock is imposed upon the nose cone at the moment of missile expulsion from the launching tube after the diaphragm 20 has been released from the end of the launching tube. A large pressure peak is imposed along the tapered portion 26 of the cone due to the combined motion of the outwardly moving ejected missile and the inwardly directed mass of inundating water. The air or pressurizing gas within the cavity, generally defined by tube 16, diaphragm 20 and missile 24, is compressed between the converging missile and water mass thus generating or producing a high pressure intensity region or concentration in the area of the missile surface defined by the tapered surface 26 of the nose cone.

The present invention accomplishes an absorption of the concentrated energy and effects a dispersal thereof to accomplish a reduction in the pressure peak to which the nose cone is subjected to a magnitude within acceptable limits. Additionally it provides support for the nose cone during transportation and minimizes the possibility of damage thereto by absorbing shock and damping vibrations reflected inwardly by the launching tube.

The invention comprises a rigid plastic foam spider 30, FIGS. 1-3, in the form of foam blocks 32 which extend from the launching tube radially inwardly into contact with the upper nose cone portion 28. The spider may be constructed of any suitable rigid plastic foam material, e.g., polyurethane. The sides of the blocks are provided with tapered recesses 34 which receive adjustment wedges 36 which permits, to a limited degree, the variation of the relationship between the arcuate surface 37 of the block adjacent the tube and the arcuate surface 38 in abutment with the nose cone. Adjustability is desirable since the tube 16 is an unmachined, generally cylindrical shaped member having inner surfaces which may not be of exact circular configuration. Also, the missile nose 28 may not be in a perfect concentrical relationship with the tube. Therefore, to assure full contact of the block surfaces with both the tube and cone under the above conditions, the appropriate wedge may be forced further into its mating recess while, simultaneously, the opposite wedge is withdrawn a like distance from the corresponding recess thus bending the block along the narrow web portion 39 as required to assure full mating contact with the cone and tube surfaces.

Supporting the foam blocks at the desired position adjacent the forward end of nose cone portion 28 is a hollow cylindrical member or barrel 40 extending from the forward circumferential row of launch/stowage adapters (not shown) to the foam blocks. The barrel member 75

may abut the blocks along the rearwardly facing surface 41 adjacent the tube wall or, preferably, the blocks and barrel member may have a tapered joint 42 as shown in FIG. 1. To insure rigidity, the blocks are secured to the barrel member by adhesive cement or other suitable fastening means. The barrel member may be composed of a number of arcuate sections, e.g. sections 40a, 40b, 40c, and 40d as shown in FIGS. 1 and 2, for ease in handling and shipping. The sections may be attached to form the cylindrical member at the time of installation in the launching tube by any suitable means. The barrel member is provided with appropriate holes 44, 45, 46 and 47 or openings to permit access to the missile for electrical, umbilical and hose connections, monitoring, and the like.

In operation, the upwardly moving ejected missile pushes the entire foam assembly 30 out of the launching tube. Upon expulsion of the missile from the tube, hydrodynamic forces acting on the foam assembly cause the foam members to separate from the missile. Due to the buoyant characteristics of the foam members, the pieces, after separation, will rise to the surface of the body of water and thus obviate fouling of the tube hatches.

The "spoke-like" configuration of the spider blocks 32 emanating radially outwardly from the missile, serves to impede and disrupt the mass of water inundating the tube after the diaphragm is released. Thus, the initial pressure peak, normally concentrated along the nose cone portion 26 due to the convergence of the missile and water upon ejection of the missile from the launching tube, is reduced to within acceptable limits as a result of the discontinuity of the water mass developed as the water impinges upon the spider.

Therefore, it will be readily apparent that the provision of the foam spider in a launching tube assembly accomplishes the objectives of providing nose cone support against shock and vibration for a missile within a launch tube in a simple and effective manner which eliminates fouling of the launch tube and favorably reduces the initial pressures imposed on the nose cone as it is ejected into the water. While the invention has herein been disclosed by reference to the details of a specific embodiment, it is understood that the foregoing disclosure is intended to be construed in an illustrative rather than limited sense, as it is contemplated that various modifications of the construction and arrangement of the parts will readily occur to those skilled in the art, within the spirit of the invention and the scope of the appended claim.

What is claimed is:

In a missile launching tube assembly having a missile contained therein for launching therefrom

substantially rigid missile positioning and shock isolating and absorbing members between the missile nose and the launching tube to position said missile and shield nose cone from excessive shock and vibration, said members being constructed of a crushable material of the character displaying high resistance to applied loads up to the point of permanent deformation thereof;

said members being formed with outer and inner arcuate surfaces, said outer arcuate surface being adjacent to and corresponding in configuration to said tube, said inner arcuate surface being adjacent to and corresponding in configuration to said nose cone, said members being formed with opposed central recesses separated by a narrow web; and

wedges insertable into said recesses, whereby in the event of misalignment said members may be bent at said web by the insertion of said wedges into the recesses thereby causing said inner and outer arcuate surfaces to change their relative curvature and to fully mate with said nose cone and said tube, respectively.
